CYLINDER HEAD

Robert H. Pennebaker, New Orleans, La.

Application January 13, 1932, Serial No. 586,410

9 Claims. (Cl. 123—173)

My invention relates broadly to internal combustion engines and more particularly to a construction of cylinder head for internal combustion engines.

One of the objects of my invention is to provide a construction of cylinder head for internal combustion engines having means for increasing the thermodynamic efficiency of the engine.

Another object of my invention is to provide a construction of cylinder head for an internal combustion engine arranged to liberate and dissipate heat rapidly for maintaining the cylinder head relatively cool and permitting the use of higher compression and the reduction of detonation effects.

Still another object of my invention is to provide a construction of cylinder head having heat absorbent members projecting into and extending outwardly from the head of the cylinder for conducting heat rapidly away from the cylinder and insuring the maintenance of the cylinder at relatively low temperature at the time the exhaust valve is open and during the exhaust and intake cycles of the engine.

A further object of my invention is to provide a construction of cylinder head having means extending into the cylinder head and projecting beyond the limits of the cylinder head and permitting the circulation of a cooling fluid such as air or water for extracting heat from the cylinder head and reducing the temperature thereof.

Another object of my invention is to provide means disposed within a cylinder head which will permit cooler running and operation of the valves, especially the exhaust valve.

A still further object of my invention is to provide a construction of cylinder head containing a multiplicity of downwardly depending thimble-like members for maintaining the temperature of the cylinder head relatively low and for increasing the efficiency of the engine.

Other and further objects of my invention reside in the construction of cylinder head for internal combustion engines as set forth more fully in the specification hereinafter following by reference to the accompanying drawing, in which:

Figure 1 is a cross-sectional view taken through an engine cylinder and illustrating an application of one form of cylinder head embodying my invention; Fig. 2 is a plan view looking upwardly into the interior of the cylinder head of Fig. 1 on line 2—2 thereof; Fig. 3 is a cross-sectional view showing a modified construction of cylinder head embodying my invention and arranged for

the circulation of fluid from the cylinder head jacket into the depending heat extracting members; Fig. 4 is a plan view taken on line 4—4 and looking upwardly into the cylinder head of Fig. 3; and Fig. 5 is an enlarged cross-sectional view of one of the thimble-like heat extracting members shown in Figs. 3 and 4.

My invention provides means for dissipating the heat which is generated at the head of the cylinder rapidly through cooling water or by the circulation of air. I provide an arrangement of thimble-like members which are directed inwardly into the interior of the cylinder head and downwardly toward the cylinder and serve to extract heat from the cylinder for rapid radiation to the cooling fluid. I may construct the heat extracting members integral with the head of the cylinder or the heat extracting members may be inserted and secured in the cylinder head. The heat extracting members may be solid or hollow in cross-section and may extend both below and above the surface forming the head of the cylinder. When tubular members are employed projecting through one wall of the cylinder head there is an opening provided in the tubular members adjacent the inner side of the wall of the cylinder head for the circulation of the cooling fluid therethrough, in cooperation with the opening at the mouth of the thimble-like member.

The rapid extraction of heat from the cylinder head serves to increase the thermodynamic efficiency of the engine and permits the use of higher compression and reduces detonation to a much further lower minimum than the present type of cylinder head with the use of the present types of fuels including high test gasoline and anti-knock fuels. The surface area of the combustion chamber is increased and the volume thereof reduced.

My invention may be embodied in a number of different constructions and the forms described particularly hereinafter are to be considered in the illustrative sense and not as limiting my invention to a particular construction.

Referring to the drawing in detail, reference character 1 designates the engine cylinder having a valve port 2 connected therewith with a valve 3 interposed between the valve port 2 and the cylinder 1. I provide a cylinder head 4 having a fluid circulating jacket 5 therein and having its lower surface equipped with the heat extracting members of my invention.

In Fig. 1 I have shown a form of my invention wherein the heat extracting members are

arranged as thimble-like projections 9. The thimble-like projections have hollow interior portions and are arranged on axes which are normal to tangents drawn to the curved wall 7 forming the interior surface of the cylinder head. The thimble-like members 9 are integrally connected with the wall 7 and have integrally formed intermediate projections 10 which extend upwardly into the fluid cooled jacket 5 in staggered relation to the members 9. The projections 10 are conical in shape and terminate in apexes within the fluid circulating jacket of the engine. The conical shaped projections 10 extend into the fluid circulating jacket for a distance which is greater than the internal diameter of the thimble-like members 10. The heat absorbed from the interior of cylinder 1 by the thimble-like members 9 is conducted upwardly through wall 7 and into the intermediate projections 10 from which the heat is dissipated into the cooling fluid in jacket 5. The spark plug serving to ignite the charge within the cylinder is indicated at 11 in Figs. 1 and 3. As shown in Fig. 2 the depending heat absorbing members 9 are spaced uniformly throughout the area of the wall 7 and serve to rapidly absorb the heat as it is liberated in the cylinder head and transmit it through the wall and projections to cooling fluid in the jacket 5 for maintaining the temperature in the cylinder head relatively low. The rows of heat extracting members extend on each side of the central area of the cylinder head and provide paths for dissipating the heat as rapidly as the heat is generated in the cylinder.

In Fig. 3 I have shown a modified form of cylinder head cooling means in which the heat extracting members have the form of tubes 12 closed at the lower ends and depending downwardly into the cylinder from the wall 7 and upwardly into the fluid cooling jacket 5 as indicated at 12a. The projections 12a extend from the wall 7 for a distance which is greater than the internal diameter of the tubes 12. Each of the tubes provides a pocket for the cooling fluid from the fluid cooling jacket 5. The structure of these tubes has been illustrated more clearly in Fig. 5 in which it will be seen that an opening 14 is provided in the side of each tube immediately above the wall 7 so that fluid standing in the hollow heat absorber 12 will not have to actually boil out before it is replaced with a fresh fluid supply, but the fluid can instead circulate through the opening 14 in the wall thereof. This circulation serves to insure a continuous supply of cooling fluid at the extremities of the heat absorbing or extracting members 12 where such heat absorption is required.

Fig. 4 illustrates the manner in which the heat absorbers are distributed on each side of the recess 15 which receives the spark plug 11, the heat extractors being arranged in rows disposed uniformly around the spark plug in the cylinder head. The downwardly depending thimble-like members 9 and 12 are arranged to absorb maximum heat from the combustion chamber without obstructing the valves arranged in the cylinder head. Fig. 5 illustrates the manner in which the tubular members are inclined with respect to the central axis of the spark plug permitting the maximum absorption of heat throughout the area of the cylinder head.

The heat absorbing or extracting members which project downwardly from the cylinder head to the interior of the cylinder resemble a porcupine arrangement. Similarly the heat dis-

tributing members which project upwardly are assembled in porcupine arrangement for the rapid dissipation of heat conducted therethrough from the heat absorbing or extracting members.

The cylinder head construction of my invention operates to substantially improve the efficiency of engine operation and permits the use of higher compression with a reduction in detonation. While I have described my invention in certain of its preferred embodiments I desire that it be understood that modifications may be made and that no limitations upon my invention are intended other than are imposed by the scope of the appended claims.

What I claim as new and desire to secure by Letters Patent of the United States is as follows:

1. In an internal combustion engine, a cylinder, a head for said cylinder, a plurality of tubular members projecting downwardly from said head toward the interior of said cylinder, and upwardly in an opposite direction to a position interior of said head, cup-shaped closures on the lower ends of said tubular members, and a cooling fluid jacket in said head surrounding the upper ends of said tubular members for conducting cooling fluid to and from said tubular members.

2. In an internal combustion engine, a cylinder, a head on said cylinder, a cooling fluid jacket in said head, a plurality of tubular members extending through said head from a position within said cooling fluid jacket to a position beneath said head in the combustion chamber of said internal combustion engine, cup-shaped closures on the lower ends of said tubular members, and a port in each of said tubular members immediately above the connection thereof with said head for providing a path for circulation of cooling fluid between each of said tubular members and said fluid cooling jacket.

3. A cylinder head for an internal combustion engine including a wall member, a plurality of tubular members extending downwardly from said wall member, cup shaped closures on the lower ends of said tubular members and projections extending from said wall member in an upward direction in staggered relation to said tubular members.

4. A cylinder head for an internal combustion engine including a wall member, a plurality of tubular members extending downwardly from said wall member, cup shaped closures on the lower ends of said tubular members and projections extending from said wall member in an upward direction in staggered relation to said tubular members, said projections each being conical in form with the apexes thereof terminating at a distance from said wall member which is greater than the internal diameter of said tubular members.

5. A cylinder head for an internal combustion engine including a curved wall member, a plurality of tubular members extending downwardly from said curved wall member and disposed over the valves and the piston in said engine, cup shaped closures on the lower ends of said tubular members and projections extending from said wall member in an upward direction with respect to said tubular members, the axes of said tubular members intersecting each other at a remote distance below said curved wall member.

6. A cylinder head for an internal combustion engine including a wall member, a plurality of tubular members extending downwardly from

5 said wall member, cup shaped closures on the lower ends of said tubular members and tubular extensions integrally connected with said wall member and with the aforesaid tubular members and projecting from said wall member for a distance greater than the internal diameter of said tubular members.

10 7. In an internal combustion engine, a cylinder, a head on said cylinder including a cooling fluid jacket defined by the walls of said head, a plurality of tubular members extending through one wall of said head from a position within said cooling fluid jacket to a position beneath said head in the combustion chamber of said internal combustion engine, cup-shaped closures on the lower ends of said tubular members, and a port in each of said tubular members immediately above the connection thereof with said head for providing a path for circulation of cooling fluid between each of said tubular members and said fluid cooling jacket, said tubular members projecting on each side of the wall of said head for distances greater than the internal diameters of said tubular members.

15 8. In an internal combustion engine, a cylinder

5 der, a head for said cylinder, a plurality of tubular members projecting downwardly from said head toward the interior of said cylinder, and upwardly in an opposite direction to a position interior of said head, cup-shaped closures on the lower ends of said tubular members, and a cooling fluid jacket surrounding the upper ends of said tubular members for conducting cooling fluid to and from said tubular members, said tubular members projecting in each direction for distances greater than the internal diameters of said tubular members.

10 9. In an internal combustion engine, a cylinder, a cylinder head defining a cooling jacket, a plurality of cylindrically shaped hollow heat extractors carried by one wall of said cylinder head and extending downwardly from said head toward said cylinder, said heat extractors being closed at their lower limits, and heat distributing members connected with the said wall of said cylinder 15 head and projecting upwardly therefrom into the cooling jacket, cooling fluid being circulated in said cooling jacket and said hollow heat extractors.
